UNITED STATES PATENT OFFICE

1,925,202

SNAPPER RACK

Laurence R. Provost, Shawnee, Kans.

Application February 4, 1932. Serial No. 590,835

1 Claim. (Cl. 211—89)

This invention relates to novel article supporting devices and has for its primary object the provision of a rack equipped with means for removably holding articles of any desirable nature such as ties, hot pads or other light units that are used often and should be hung where it is not difficult to secure or remove the same from their proper place.

One of the important objects of the present invention is the contemplation of a rack particularly constructed to support ties, said rack including a plurality of fingers, beneath which the ties may be placed with ease and removed by a quick jerk necessitating the use of but one hand, yet not injuring the tie in any manner.

A further aim of this invention is to provide a cheaply constructed, useful rack that may be hung on the wall for the purpose of receiving and holding light articles which should be available and removable from the rack without endangering the security of all the articles remaining thereon which are not to be removed.

A still further object of the invention is the contemplation of a simple, efficient, and unique rack having thereon a plurality of fingers, one end of each of which is yieldably maintained against the base of the rack whereby to hold light articles thereagainst.

A yet further object of this invention is the provision of a rack structure, wherein is included a plurality of fingers, all of which are supported by the base of said rack by common means which, in some instances, may be slidably or otherwise removably affixed to the base, whereby the assembly of the parts of said rack is rendered exceptionally inexpensive.

Many minor objects of the invention, especially relating to the specific structure of a rack embodying the invention, will appear during the course of the following specification, referring to the accompanying drawing, wherein:

Figure 1 is a face view of a rack made in accordance with the preferred form of the instant invention.

Fig. 2 is a top, edge, plan view of the same.

Fig. 3 is a cross section through the rack, taken on line III—III of Fig. 1.

Fig. 4 is a fragmentary, longitudinal, detailed section through a portion of the rack taken on line IV—IV of Fig. 1.

Fig. 5 is a fragmentary, face view of a rack made to embody a modified form of the invention, and,

Fig. 6 is a cross section through the rack, embodying the same modified form.

In describing the parts which are combined to form a novel rack contemplated by this invention, like reference numerals will be used to designate similar parts throughout the several views of the drawing. The preferred form illustrated in Figs. 1 to 4 inclusive shows a rack having a base 8 formed of any suitable material such as aluminum or sheet metal and flanged at 10 to insure rigidity. It is preferred to provide base 8 with two or more openings 12, by means of which the rack may be hung in place, and the articles supported thereby moved therefrom without setting up an objectionable swing. The design of base 8, clearly shown in Fig. 1, has been found pleasing and practical, and one cheap to manufacture. In this instance ears 14 form openings 12, which may receive screws, nails, or other securing means to affix the rack to a wall. It is understood that base 8 may be formed of molded material or cut from comparatively thin wood or composition board, all being within the concepts of the present invention.

A plurality of fingers 16 are carried by base 8 so that one end thereof bears thereagainst, while the other end is spaced therefrom, as shown in Fig. 3. A U-shaped spring or similar resilient member 18 joins finger 16 intermediate the ends thereof to rockingly support said finger in a manner whereby movement of one end thereof toward the base will lift the other end therefrom.

In most instances it is desirable to provide common means for operatively supporting fingers 16 upon base 8. In the preferred form, a strip 20 is supplied for this purpose and formed to present a longitudinal bead 22, through opposite walls of which is formed openings 24 for the reception of the aforementioned U-shaped spring 18. The manner of inserting this spring is clearly shown in Fig. 3.

Fingers 16 are spaced apart throughout the length of strip 20, and after their assembly therewith, the unit is moved to place in association with base 8 by sliding strip 20 beneath a number of ears 26. To stop this sliding movement and to position strip 20 on base 8 and preclude its accidental displacement after it has been moved to place, lips 28 are struck from base 8 and angled slightly outwardly, as shown in Fig. 4. When inserting strip 20, lip 28 over which it is passing is simple pressed inwardly until the end of strip 20 is reached and lip 28 snaps up thereagainst.

The end of each finger 16 which engages base 8 should be formed to present a head 30 which will allow the article being held therebeneath to be pulled from its supported position by a quick

jerk without the danger of injury. The construction just above set forth permits plating fingers 16 and strip 20 after they have been assembled and before they are placed upon base 8. It likewise allows spraying or otherwise dec-
5 orating base 8 without having to exercise caution which naturally would increase the manufacturing cost of the rack.

It is obvious that any number of fingers 16
10 may be used in making a snapper rack and that any type of base suitable for the many particular uses might be formed. Manifestly, the broad concepts of the invention might be embodied in structures of various natures, and it has been
15 deemed advisable to illustrate one modification such as Figs. 5 and 6 of the accompanying drawing.

Referring now to Fig. 5 and 6, base 50 should be made of sheet metal or other material having
20 properties which allow the formation of a longitudinal bead 52 through opposing side walls of which is formed appropriate openings to receive one leg of U-shaped spring 54 similar in design and function to member 18 of the preferred form.

Finger 56 having a head 58 formed thereon is affixed to spring 54 so that its one end bears against the face of base 50. The other end being spaced apart therefrom permits movement of head 58 toward and from base 50 as the article to be held is inserted beneath finger 56.

Obviously, any number of fingers 56 might be carried by bead 52 along its length, and while this single bead is the sole supporting member for all fingers 56, it cannot be moved to carry members 56 out of the operative relation with base 50.

Many other embodiments of the invention might be set down and it is desired to practice the advantages of the present invention so long as the same falls within the scope of the appended claim.

Having thus described the invention, what is claimed as new and desired to be secured by Letters Patent is:

A rack comprising a base; a series of ears struck from said base; a strip slidably secured to said base beneath said ears; and a plurality of rockingly mounted fingers on said strip.
